UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

PACKAGE AND PROCESS OF MAKING IT.

Application filed July 7, 1921. Serial No. 482,942.

To all whom it may concern:

Be it known that I, ADELMER M. BATES, a citizen of the United States, residing at Chicago, in the county of Cook and State of Illinois, have invented a certain new and useful Improvement in Packages and Processes of Making Them, of which the following is a specification.

My invention relates to an improved package, and a process for forming it, and particularly to packages adapted for holding material such as flour, rice and the like, and particularly also to packages made of paper or similar material. The package in general terms comprises a tube of paper closed at each end by a reinforced seam, the length of the bag closing portion of the seam being substantially equal to the diameter of the filled bag or package in the direction of the seam and less than the width of the tube when collapsed without inward folds. The side walls of the package adjacent the seams are inwardly folded to reinforce and shorten the seams. The package illustrated is made of crinkled paper which will expand something like 30 per cent of its length before tearing.

My invention is illustrated more or less diagrammatically in the accompanying drawings, wherein—

Figure 1 is a side elevation of the package;

Fig. 2 is an end elevation;

Fig. 3 is a plan view of the package,

Fig. 4 is a section through the end of the tube at the place where the seam is to be formed, and

Fig. 5 is a diagrammatic view of a means for forming the package from a tube.

A is a tube of crinkled paper, though of course it might be of cloth or membranous material, or even of smooth, tough paper. A¹ is a pasted longitudinal seam, although this might be a sewn seam. If it were sewn, the seam would probably be inside, the tube having been reversed after sewing. A² A² are the inwardly bent ends of the tube forming the ends of the package and joined together by the seam A³.

The seam A³ is made up of the two parallel reinforcing members B B, which members are sewn together by stitches B¹ B¹

of thread or the like extending through the reinforcing members and through the package material to form a reinforced seam.

C C are inwardly bent portions of the tube between the portions A² A² and these inwardly bent portions terminate in accordion folds C¹ C¹, which are sewn into the seam so that the corners of the bag at the ends of the seam are reinforced as at C², there being at this point four thicknesses of the paper or other fabric instead of two, and these four thicknesses being also reinforced by the reinforcing members. Thus the four corners of the package at the ends of the seam, which are the points likely to support the heaviest load and likely to be the weakest parts of the bag, are reinforced both by the folding of the bag and by the presence of the reinforcing members tied together by the holding seam. As will be noted, the inwardly bent portions C form a hand hold of advantage in handling the bag and the reinforced seam may be gripped readily without tearing the bag.

The process of forming the package from a tube may be made easier by a prefolding of the tube before the charge of material is placed therein. In such a case the tube is folded or collapsed, as illustrated in Fig. 4, the accordion pleats therein, lettered C¹, running from end to end of the tube when in collapsed condition. In the process illustrated, an elongated tube, thus prefolded, is fed forward about any preferred bag-filling means, such as a filling tube D, and the tube is collapsed longitudinally thereabout. The bottom closure is then formed by puckering or pleating the bottom of the tube as above described, the tube being sewed across to form the type of seam and reinforced bag end illustrated in Figs. 2 and 3. A charge of material is then fed into the bag section and the operator then closes the upper portion of the bag section by folding the bag inwardly at opposed points on the preformed folded or creased portion of the tube. The opposed sides of the bag are thus collapsed, and the operator then passes the collapsed portion of the bag through any means E adapted to sew the reinforced seam above described. The section thus formed is then severed from the tubing along line parallel

with and closely adjacent to the seam, the bottom of the next section being simultaneously formed by another seam, and the process is thus continued. When the closures are made in this way the ends of the folds are cut off beyond the seam flush with the sides of the package. In this way each fold is caught into the seam clear to its apex.

10 While I have described in some detail a package and one method of making the same, I regard as essential only those features stated in the several appended claims. I have shown a particular closure applied to 15 both ends of a filled package, but the broader claims are applicable where the closure is used at only one end of a bag or package. The closure is shown with reinforcing members on each side, but in some instances reinforcing elements may be dispensed with or used on one side only, and numerous other changes may be made in the article and process within the scope of the appended claims without departing 20 from the spirit of the invention.

25 I claim:

1. As an article of manufacture, a package comprising a body portion, an end closure formed by a seam substantially equal in length to the width of the body portion when filled, the walls of the body portion being folded in adjacent the closure to form a reentrant pocket at each end of the seam and the seam being formed by sewing 30 through the walls, including the infolded portions.

2. As an article of manufacture, a bag comprising a body portion, a stitched closure and a reinforcing element extending entirely 40 across the closure and held in place solely by the stitches of the closure, the walls of the body portion being folded in adjacent the closure to form a reentrant pocket at each end of the seam and the seam being formed by sewing 45 through the walls, including the infolded portions.

3. As an article of manufacture, a package comprising a tubular bag body cut off across each end and closed by seams, the tube 50 wall being folded in to form a reentrant pocket at each end of each seam and the seam being formed by sewing through the walls, including the infolded portions.

4. As an article of manufacture, a package comprising a tubular bag body cut off across each end and closed by seams, a reinforcing element extending across each end closure and held in place thereon solely by the stitches of the seam, the tube wall being 60 folded in to form a reentrant pocket at each end of each seam and the seam being formed by sewing through the walls, including the infolded portions.

5. As an article of manufacture, a bag comprising a tubular bag body cut off across

an end and closed by a seam, a reinforcing element extending entirely across said closure, the tube wall being folded in to form a reentrant pocket at each end of the seam and the wall, including the infolded portions, being trimmed off beyond and parallel 70 with the seam.

6. As an article of manufacture, a bag having an end folded inwardly on two opposite sides and closed by a seam stitched 75 through the sides and folds, the sides and folds extending through the seam an equal distance at all points.

7. As an article of manufacture, a bag having an end folded inwardly on two opposite sides and closed by a seam stitched 80 through the sides and folds, the apex of each fold extending through the seam.

8. As an article of manufacture, a bag comprising a tubular bag body, a stitched 85 closure across an end of the body and a reinforcing element extending along said closure on each side of the bag and held in position solely by the stitches of the closure, the walls of the bag body being folded in at 90 each end of the closure and the stitches passing through the walls at the apex of each fold.

9. As an article of manufacture, a package consisting of filling material and a bag 95 of crinkled paper having its sides folded in at each end and a transverse seam across each end through the bag sides and folds, the apex of each fold extending into a seam.

10. As an article of manufacture, a bag 100 of crinkled paper having its sides folded in at an end and a transverse seam across such end through the bag sides and folds, the apex of each fold extending into the seam.

11. As an article of manufacture, a bag having an end folded inwardly at two opposite sides, a reinforcing element extending across the end, the ends of the element extending beyond the sides of the bag, and a 110 seam stitched through the entire length of the element and through the sides and folds of the bag, the apex of each fold extending through the seam.

12. As an article of manufacture, a package 115 consisting of filling material and a bag of crinkled paper having its sides folded in at each end, a reinforcing element across each side of each end, said elements extending beyond the sides of the bag, and a transverse seam across each end through the bag sides and folds and through said element, the apex of each fold extending into the seam.

13. As an article of manufacture, a package 125 consisting of filling material and a bag of crinkled paper having its sides folded in at an end, a reinforcing element extending across the bag and beyond its sides, and a transverse seam across such end through the 130

bag sides and folds and through said element, the apex of each fold extending into the seam.

14. As a new article of manufacture, a package substantially rectangular in cross section, two of the opposed walls being inwardly folded toward one another, the other two opposed walls being brought together to grip the folded walls, reinforcing strips applied to each of the unfolded walls and projecting beyond said walls at both ends and a seam joining said strips and walls and holding them together to form a closure, the strips being sewn together at each end beyond the package walls.

15. The process of forming a closure for the end of a bag, which consists in folding inwardly diametrically opposed points on the bag walls, collapsing the bag against these folds, then positioning a reinforcing member on each side of the collapsed portion and sewing through the reinforcing members, bag walls and folds.

16. The process of forming a closure across a tube between its ends, which consists in folding inwardly diametrically opposed points on the tube, collapsing the tube against these folds, then positioning a reinforcing member across the collapsed portion of the tube and sewing through the reinforcing member, tube walls and folds to form a closure.

17. In the production of bags from an elongated tube closed at one end, folding inwardly opposite sides of the tube, collapsing the tube sides against the folds, sewing transversely through the tube sides and folds a bag's length distant from the closed end to form a tube closing seam, and severing the tube adjacent the seam.

18. In the production of bags from an elongated tube closed at one end, folding inwardly the sides of the tube, collapsing the tube sides against the folds, positioning a reinforcing member transversely on a side of the collapsed tube a bag's length distant from the closed end of the tube, sewing

through the reinforcing element, the tube sides and the folds to form a tube closing seam, and severing the tube adjacent the seam.

19. In the production of bags from an elongated tube, folding inwardly diametrically opposed points on the tube, collapsing the tube sides in a direction normal to the folds, sewing two adjacent transverse seams through the tube sides and folds, and severing the tube between the seams.

20. In the production of bags from an elongated tube, folding inwardly diametrically opposed points on the tube, collapsing the tube sides against the folds, positioning two pairs of reinforcing elements adjacent each other transversely of the tube, one element of each pair on each side of the tube, sewing a tube closing seam through each pair of reinforcing elements and the intervening tube sides and folds, and severing the tube between the seams.

21. The process of closing the open end of a filled package, which consists in inwardly folding two opposed sides of the package tube, and collapsing the other two opposed sides together with the inwardly folded sides between them, then laying along the outside of one of said collapsed side walls a reinforcing strip, sewing the strip and the folded and collapsed walls all together to form a reinforced closing seam and cutting off the walls beyond the seam parallel therewith.

22. The process of closing the open end of a filled package, which consists in inwardly folding two opposed walls adjacent such open end, collapsing the other two opposed walls together with the inwardly folded portions between them to close the open end, then laying reinforcing strips along the outside of both of said side walls and sewing the strips and the tube walls together to form a reinforced closing seam.

In testimony whereof, I affix my signature this 1st day of July 1921.

ADELMER M. BATES.
